[57] CLAIM

The ornamental design for a table base, as shown and
described.

DESCRIPTION

FIG. 1 is an isometric view of a table base showing my
new design;

FIG. 2 is a side elevational view thereof;

FIG. 3 is a top plan view thereof;

FIG. 4 is a fragmentary cross-sectional view, taken
along line 4—4 in FIG. 3;

FIG. 5 is a side elevational view showing one of the legs
for convenience of illustration;

FIG. 6 is a top plan view thereof; and,

FIG. 7 is a front elevational view thereof.
